[57] CLAIM

The ornamental design for a directional indicating band for attachment to fire fighting hose, as shown and described.

DESCRIPTION

FIG. 1 is a front top perspective view of a directional indicating band for attachment to fire fighting hose showing my new design;

FIG. 2 is a top plan view thereof;

FIG. 3 is a bottom plan view thereof;

FIG. 4 is a right side elevational view thereof, the left side being a mirror image of the right side;

FIG. 5 is a front elevational view thereof;

FIG. 6 is a rear elevational view thereof;

FIG. 7 is a front top perspective view of a second embodiment thereof;

FIG. 8 is a top plan view of FIG. 7, the bottom being a mirror image of the top;

FIG. 9 is a right side elevational view of FIG. 7, the left side being a mirror image of the right side;

FIG. 10 is a front elevational view of FIG. 7; and,

FIG. 11 is a rear elevational view of FIG. 7.

It is to be understood that the views have been shaded to indicate contrasting color.
